UNITED STATES PATENT OFFICE.

CHARLES F. KEWITZ, OF LAKewood, OHIO.

EJECTING MECHANISM.

1,106,570.

Specification of Letters Patent. Patented Aug. 11, 1914.

Application filed August 22, 1913. Serial No. 786,086.

To all whom it may concern:

Be it known that I, CHARLES F. KEWITZ, a citizen of the United States, residing at Lakewood, in the county of Cuyahoga and 5 State of Ohio, have invented a certain new and useful Improvement in Ejecting Mechanism, of which the following is a full, clear, and exact description, reference being had to the accompanying drawings.

10 This invention relates to article stackers, and ejecting machinery and particularly to an ejecting mechanism for book binding machines although the arrangements here disclosed are equally applicable to printing 15 machinery, envelop sealers, stampers, or cancelers, folding machines, box making machines, package fillers, and other uses too numerous to mention. However for purposes of disclosure I have illustrated and 20 described the device in connection with a book stitching machine, since the employment of my improvements serves to obviate many difficulties to which these machines are peculiarly subject, although I do not 25 propose to confine myself to such use.

In certain well-known and widely used stitching machines, such, for example, as that shown in the patent to Kugler, No. 795,623, dated July 25, 1905, pamphlets or 30 signatures are stitched, one at a time, with thread, the thread being continuous so that all of the signatures or pamphlets are secured together at their backs, and each new signature or pamphlet after being stitched 35 is pressed against the rearward end of the series of already stitched signatures or pamphlets so that the whole stack or pile is gradually advanced. It is the usual custom to support these signatures or pamphlets in 40 vertical position with their backs up and to move them in a horizontal direction, some sort of a block or weight being frequently employed for holding these pamphlets or signatures in upright position. At intervals, 45 an attendant will remove a greater or smaller number of the completed signatures or pamphlets, breaking or cutting the thread at that point. However, it has been found that these signatures or pamphlets 50 tend to bind in the guideway owing to their

weight and friction, or to fall over forwardly owing to the pressure from behind, or to fall rearwardly against the needle and into the path of the approaching pamphlets, and considerable inconvenience has been 55 caused by the clogging of the machine and the breaking of needles.

Accordingly, it is the object of this invention to provide mechanism for conveying these signatures or pamphlets, at the 60 proper rate, away from the operating portion of the machine to the end that such clogging of the machine and interference with its function may be eliminated.

Other objects are the provision of means 65 in such a device for regulating or varying the amount of feed depending upon the thickness of the pamphlet or other articles; the provision of means for adjusting the pressure of contact of those pamphlets or 70 articles with the advancing means, depending upon the weight of the same; the provision of a simple alarm or indicator, whereby the attendant may be warned when the rack has become full so that the pamphlets or 75 articles may be removed; while further objects and advantages of the invention will become apparent as the description proceeds.

Generally speaking my invention may be 80 defined as consisting of the combinations and constructions recited in the claims here-to annexed and illustrated in the drawings accompanying and forming part of this application, wherein:

Figure 1 is a side elevation of a stitching machine provided with my improved attachment; Fig. 2 is a detail view taken immediately beside my attachment and showing only so much of the stitching mechanism as is essential to understand the operation of the attachment; Fig. 3 is a top plan view of the stacking table, together with the devices of my invention; Fig. 4 is a detail view showing in side elevation the feed 90 mechanism which I employ; Fig. 5 is a bottom plan view of the same mechanism; Fig. 6 is a vertical cross-sectional view taken upon the lines 6—6 of Fig. 2 and looking in the directions of the arrows, the sprockets 95 100

being shown in elevation, and Fig. 7 is a bottom plan view of the parts shown in Fig. 3.

Describing the parts by reference characters, 1 represents the frame or standard of a stitching machine, 2 the fly wheel or drive wheel, 3 the stitcher arm, 4 the needle plunger, 5 the plunger-operating arm, 6 the needle and 7 the needle shoe. In the machine here illustrated the pamphlets to be sewed are supported upon a V-shaped anvil 10 carried on the upper end of an arm 11, the latter being pivoted at 12 upon a horizontal axis so as to be swung toward and from the frame of the machine, as shown in full and dotted lines in Fig. 2. The sides of the anvil are formed of flat plates 13, 14 respectively, spaced apart or apertured at the apex as shown at 14^a, the plate 13 being so disposed relatively to the arm 11 as to be positioned substantially vertically when that arm is in forward position, as shown in full lines in Fig. 1 and in dotted lines in Fig. 2. By suitable mechanism, not necessary to be described for purposes of the present application, the needle is operated in phase with the movement of the arm, so that upon the forward movement of this arm, the needle may be advanced into the slot or aperture 14^a, whereupon knotting, looping, or tying mechanism is actuated to secure the thread.

Mounted between the side members of the machine frame at the opposite side of the needle shoe from the anvil is a stacking table 15 for the reception of the signatures or pamphlets after they are sewed. This table is generally secured in a horizontal position so as to support the pamphlets without any tendency of the same to move bodily in one direction or the other, and is raised or lowered as necessary for the reception of the pamphlets or signatures by means of a rack 16 and pinion 17, the adjustment, when secured, being rendered permanent by means of a suitable set screw 18. A guide rod 19 coöperating with a sleeve 20 carried by the machine frame, may be employed to maintain the platform 15 in rigid position. The height of the shoe 7 is such that the anvil 10 with the pamphlet thereon may just swing therebelow; and the height of the table is adjusted so that the edges of the leaves may just clear the same.

In the operation of the machine, the arm 11 swings to the position shown in full lines in Fig. 2; an attendant places a pamphlet or signature upon the anvil in open position with the back of the same coinciding with the apex; the arm then swings to the position shown in dotted lines in Fig. 2; the needle is depressed perforating the sheet and carrying the thread through the paper; the threads are looped, twisted, or knotted,

depending upon the operation of the machine; and the needle is withdrawn. Thereupon, the arm 11 swings back to its original position for the reception of another pamphlet, the first pamphlet being left upon the stacking table by reason of the fact that the thread with which it is sewed is not severed from the preceding pamphlet. The attendant now places another pamphlet upon the arm after which the latter is again swung so as to carry the new signature or pamphlet into the range of operation and the pamphlet or signature already sewed is shoved along the table a distance dependent upon its thickness and that of the pamphlet being brought up.

Inasmuch as the threads are not cut, the stacking table soon becomes filled with the pamphlets all sewn together at their backs, and the weight and friction of these pamphlets and their tendency to buckle, bind and fall over, sometimes blocks the operation of the machine and frequently causes delay by breaking needles. In order to overcome this difficulty I provide the lower face of the table 15 adjacent to each corner with a depending bracket 25, and in these brackets I journal parallel horizontal transverse shafts 26 and 27. Upon each of these shafts I secure a pair of spaced sprocket wheels 28, 28 the table 15 being provided with a pair of slots 29 adjacent to each end through which these sprocket wheels may project. Around these sprocket wheels I pass chains 30, 30, the portion of these chains which lies above the table resting flat upon the surface of the table and being thereby supported in a smooth and horizontal manner. The teeth of the sprocket wheels, particularly at the receiving end of the table, are preferably slightly longer than the thickness of the chain so as to project therethrough a short distance as shown at 31.

Carried by one of the shafts, as 26, is a ratchet wheel 32, and secured to the table 15, adjacent to the ratchet is a reciprocable slide 33. In the present embodiment, this slide consists of a metal block having therein a pair of slots 34 receiving the screws 35, 35 by which it is secured to the table 15. Adjustably secured to one face of this block is a plate 36, so arranged as to be shifted longitudinally thereof and clamped in any desired position of adjustment. Pivoted to the end of the block opposite to that beyond which the plate 36 projects is a pawl 37, said pawl being, in the present instance, formed in two parts the better to prevent accidental failure to operate. The block 33 is normally held in retracted position by means of the spring 38, and the location of the parts is such that the end of the plate 36 will project into the path of movement of the plate 18 or other suitable portion of the anvil.

In order to prevent the whole weight of the pamphlets from being impressed upon the chains 30, I preferably provide the table 15 with a plurality of spaced parallel friction strips 40, 40, the same being supported upon the ends of thumb screws 41. Also, in order to prevent the pamphlets from falling over or crumpling of their own weight, a retarding block 42 may be provided, as 10 shown in Figs. 2 and 6, said block preferably having its lower face notched or grooved, as at 43, so as not to be engaged by the chains.

With this construction it will be seen that, upon each swing of the arm 11, the plate 15 will come in contact with the end of the plate 36, displacing the block 33 and rotating the ratchet wheel 32, whereby the sprockets 28, 28 and chains 30, 30 are advanced. Upon the movement of the arm in 20 the opposite direction, the block returns to its former position and the pawls take a new position on the ratchet ready for the repetition of the operation.

Adjustment for pamphlets or signatures 25 of different thickness is effected by means of the plate 36, since the greater the distance beyond the block this extends, the earlier it will be contracted by the plate 13 and the greater will be the displacement of 30 the ratchet wheel. Of course the fineness of this adjustment will depend entirely upon the pitch of the ratchet, but that is not important, since I find by experience that the machine works best when the conveyer mechanism operates at a slightly greater speed 35 than the signatures or pamphlets are fed thereto, thus tending to separate the pamphlets instead of permitting any crowding of the same. The sprocket teeth project 40 slightly through the chain, as previously stated, and engage the edges of the sheet positively so as to prevent any failure of progression, although the flexibility of the sheets is such as to cause them to slip back- 45 wardly past the teeth before any material grounding is caused.

It will be noted that, in any case the pamphlets between the receiving end of the table and the center of the first sprocket 50 wheel will be moved entirely by the arm and not by the chain. The friction strips 40, 40 will be adjusted by means of the thumb screws 41, 41 to that height which experience may show to be most advantageous with signatures or pamphlets of a given weight. Inasmuch as the chains may travel more rapidly than the pamphlets there must be some slipping and it is sometimes necessary to reduce the friction so as to permit this slipping. The fact that the retarding block 60 rests only upon the friction strips and not upon the chains causes it to hold the books or pamphlets from progressing too rapidly. Also one pair of slots is made of greater

width than the other pair of slots as shown 65 in Figs. 3, 6 and 7, and the corresponding sprocket wheels are slidably secured upon their shafts, as illustrated at 42, so that the distance between the chains can be adjusted, depending upon the length of the signatures 70 or pamphlets.

In order to apprise the attendant or operator that the stacking table is becoming full, a great many expedients could be employed, as will be obvious, but the simplest 75 which occurs to me is that illustrated in Figs. 1 and 2 thereof, and consists of a bell 45 secured at the discharging end of said table and a suitable wire or arm 46 pivoted to the end of the table and having at its end 80 a striker 47. The middle portion of this arm is deflected laterally, as at 48, so as to render the arm unbalanced, thus tending to retain it in upright position when turned in that way, and also causing it to be engaged 85 by the face of the block 42 upon the approach of the same, whereupon it falls to the position shown in dotted lines in Fig. 2, ringing the bell and apprising the attendant that the table is full. 90

While I have chosen, for purposes of illustration, a book stitching machine of the type illustrated in the patent to Kugler, 795,623 hereinbefore referred to, I do not limit myself to use with that machine, or with that 95 class of machines since there are many machines to which my attachment may be applied with beneficial results and without the exercise of anything excepting ordinary mechanical skill. Also, while I have described 100 in detail the particular construction and arrangement of the parts of my invention, I have done so merely for purposes of illustration and not with the idea of limitation, wherefore, I do not propose to limit it 105 to such details, except as the same may be positively included in the claims hereto annexed or may be rendered necessary by the prior state of the art.

Having thus described my invention, what 110 I claim is:—

1. In a stacking mechanism of the type wherein successive paper articles are delivered in vertical position to a horizontal receiving table and are advanced along that table by the operation of a ramming device acting upon each article as it is delivered, the combination, with such table and ramming device, of means for attaching the uppermost edge of each newly delivered article to the corresponding edge of the next preceding article, conveyer mechanism projecting above the surface of said table and arranged to bear against the lowermost edges of said articles, and means for advancing said conveyer mechanism intermittently. 115 120 125

2. In stitching mechanism, the combina-

tion with a needle shoe, a vertically adjustable stacking table located beneath said shoe, and a ramming device movable toward and from said table and arranged to deliver articles singly to said table and to press them against the articles already in place thereon, of means for securing each article to the succeeding article as it passes beneath said shoe, conveyer mechanism carried by said 5 table and upon which said articles may bear, means for advancing said conveyer mechanism intermittently substantially simultaneously with the addition of succeeding articles to the end of the series, the amount of 10 advance movement at each step being at least as great as the thickness of the articles added.

3. In ejecting mechanism of the type wherein flexible paper articles are delivered 20 in succession to a stacking table and advanced along that table by the addition of succeeding articles to the rear end of the series, the combination, with the stacking table, of an endless chain projecting above 25 the surface of said table and upon which said articles may bear, sprocket wheels journaled to the table and having teeth engaging said chain, the length of the teeth being greater than the thickness of the chain and 30 the position of the wheels being such as to cause said teeth to project above the surface of the table and engage the articles directly, and means for advancing said sprocket wheels intermittently substantially simultaneously with the addition of succeeding articles to the end of the series, the amount of 35 advance movement at each step being at least as great as the thickness of the articles added.

4. In ejecting mechanism of the type wherein paper articles are delivered in succession to a stacking table and advanced along that table by the addition of succeeding articles to the rear end of the series, 45 the combination, with the stacking table, of conveyer mechanism projecting above the surface of said table and upon which said articles may bear, supporting members adjacent to and parallel with said conveyer 50 mechanism and adapted to relieve the latter of a portion of the weight of said articles, and adjustable means for variably advancing said conveyer mechanism intermittently substantially simultaneously with the addition of 55 succeeding articles to the end of the series.

5. In ejecting mechanism of the type wherein paper articles are delivered in succession to a stacking table and advanced along that table by the addition of succeeding 60 articles to the rear end of the series, the combination, with the stacking table, of conveyer mechanism, projecting above the surface of said table and upon which said articles may bear, supporting members ad-

jacent to and parallel with said conveyer 65 mechanism and adapted to relieve the latter of a portion of the weight of said articles, means for adjusting said supporting members toward and from the top of said table so as to vary the proportion of weight carried thereby, and means for advancing said 70 conveyer mechanism intermittently substantially simultaneously with the addition of succeeding articles to the end of the series, the amount of advance movement at each 75 step being substantially proportional to the thickness of said articles.

6. In ejecting mechanism of the type wherein paper articles are delivered in succession to a stacking table and are advanced 80 along that table by the operation of a ramming device acting upon each article as it is delivered, the combination, with such table and ramming device, of conveyer mechanism adapted to engage and advance said articles, means projecting into the path of movement of said ramming device and adapted to be displaced upon the advancing movement thereof, and connections between said means and said conveyer mechanism whereby the 85 latter will be shifted forwardly one step upon each advancing movement of said ramming device.

7. In ejecting mechanism of the type wherein paper articles are delivered in succession to a stacking table and are advanced along that table by the operation of a ramming device acting upon each article as it is delivered, the combination, with such 90 table and ramming device, of conveyer 100 mechanism adapted to engage and advance said articles, a reciprocable member, means carried by said member and projecting into the path of movement of said ramming device so as to be displaced together with said 105 member upon the advancing movement thereof, and connections between said member and said conveyer mechanism whereby the latter will be advanced upon the forward movement of the former, said means 110 being adjustable relatively to said member whereby the amount of displacement can be varied.

8. In ejecting mechanism of the type wherein paper articles are delivered in succession to a stacking table and advanced along that table by the addition of succeeding articles to the end of the series, the combination, with the stacking table, of a plurality of vertically adjustable, parallel, 115 friction strips carried by said table, a plurality of conveyer members located between said friction strips and adapted to bear against the lowermost portions of said articles, and means for advancing said conveyer members intermittently, substantially simultaneously with the addition of succeeding 120 articles to the end of the series, the amount 125

of such advance movement at each step being greater than the thickness of such articles.

9. In mechanism of the character described, the combination, with a shoe and a substantially horizontal stacking table having slots therein, and supported beneath the same, said table being vertically adjustable, of flexible conveyer devices passing through said slots, a portion of such conveyer devices projecting above the upper surface of said table, a reciprocable ramming device arranged in line with said conveyer devices and arranged for feeding paper articles singly to the end of said table, and means carried by said table and arranged to be engaged by said ramming devices upon the advancing movement of the same for advancing said conveyer devices substantially simultaneously with the feed of said articles.

10. The combination with a stacking table, and means for feeding paper articles thereto singly and pressing the same against the articles already on said table, of a pair of shafts journaled adjacent to said table, wheels carried by said shafts, flexible conveyer devices passing around said wheels, a portion of said conveyer devices passing along the upper face of said table, stationary friction strips carried by said table adjacent to and parallel with said conveyer members, and means for advancing said conveyer devices intermittently substantially simultaneously with the application of new articles to the end of the series.

11. The combination with a stacking table, and means for feeding paper articles thereto singly and pressing the same against the articles already on said table, of a pair of shafts journaled adjacent to said table, sprocket wheels carried by said shaft, chains passing around said sprocket wheels and overlying said table, said table being slotted for the passage of said chains, a ratchet wheel on one of said shafts, and means for advancing said ratchet wheel simultaneously with the application of a new article to the end of the series, and means for adjusting the amount of feed of said ratchet wheel.

12. The combination with a substantially, horizontal stacking table for paper articles and reciprocating means whereby succeeding articles may be pressed against the face of articles already on said table whereby the whole series of articles is advanced, of conveyer mechanism carried by said table and projecting above the surface thereof and adapted to receive said articles, ratchet means operatively associated with said conveyer mechanism, a reciprocating device carried by said table and adapted to project beyond the end thereof into the path of said

reciprocating means, and pawls secured to said reciprocating device and engaging said ratchet means so as to move said conveyer mechanism upon the forward movement of said reciprocating means.

13. In ejecting mechanism of the type wherein paper articles are delivered in succession to a stacking table and advanced along that table by the addition of succeeding articles to the rear end of the series, the combination, with the stacking table, of conveyer mechanism projecting above the surface of said table and upon which said articles may bear, supporting members adjacent to and parallel with said conveyer mechanism and adapted to relieve the latter of a portion of the weight of said articles, means for advancing said conveyer mechanism at a speed more rapid than the speed of advance of said series, and a retarding block carried by said table in advance of said series of articles, said block being entirely out of contact with said conveyer mechanism.

14. In ejecting mechanism of the type wherein paper articles are delivered in succession to a stacking table and are advanced along that table by the operation of a ramming device acting upon each article as it is delivered, the combination, with such table and ramming device, of friction strips carried by said table adapted to receive and support said articles, conveyer mechanism carried by said table and adapted to bear against the lowermost portions of said articles, means for operating said conveyer mechanism at a speed greater than the speed of advance of said articles, means for adjusting said strips toward and from the table so as to vary the pressure with which they bear against said articles, and a retarding block carried by said table in advance of said series of articles, the bottom portion of said block being cut away so as not to contact with said conveyer mechanism.

15. The combination, with a substantially, horizontal stacking table and a reciprocating member whereby paper articles are delivered in succession to said table and are advanced therealong, of a pair of parallel, horizontal, transverse shafts journaled to the lower side of said table and having sprocket wheels thereon, said table being slotted for said sprocket wheels, chains passing around each pair of sprocket wheels, a portion of each chain overlying the surface of said table, a ratchet wheel carried by one of said shafts, a pawl co-operating with said ratchet wheel, and reciprocating means projecting into the path of movement of said reciprocating member and operatively connected to said pawl, the sprocket wheels of one pair being adjustable longitudinally of their shafts whereby the distance between said chains may be varied.

6

16. In ejecting mechanism, the combination, with a stacking table and means for delivering articles thereto in succession and advancing the same in series therealong, of
5 alarm mechanism for indicating the fullness of the table comprising a sounding member fixed to the table, and a striking member pivoted to said table and adapted when displaced to strike said sounding member, said

striking member having an offset portion 10 adapted to be engaged and displaced by the approach of said articles.

In testimony whereof, I hereunto affix my signature in the presence of two witnesses.

CHARLES F. KEWITZ.
